OAR REST

Edward J. Scheckel, La Grange, Ill.

Application November 12, 1946, Serial No. 709,132

2 Claims. (Cl. 9—1)

1

This invention relates to an oar rest and it is an object of the invention to provide a device of this kind which can be readily mounted upon the gunwale of a boat in substantially a fixed or permanent position.

It is also an object of the invention to provide a device of this kind which is mounted upon the gunwale of a boat in a manner whereby it can be readily swung out into operative position or when not in use can be readily thrown inwardly out of the way to minimize liability of it becoming damaged.

It is also an object of the invention to provide a device of this kind which, when extended for use, is supported in an effective manner to withstand the load of the oar resting thereon.

The invention consists in the details of construction and in the combination and arrangement of the several parts of my improved oar rest whereby certain advantages are attained, as will be hereinafter more fully set forth.

In order that my invention may be better understood, I will now proceed to describe the same with reference to the accompanying drawings, wherein:

Figure 1 is a view partly in section and partly in elevation illustrating an oar support constructed in accordance with an embodiment of the invention and in extended or working position;

Figure 2 is a view similar to Figure 1 showing the support in an inoperative position;

Figure 3 is a view in top plan of the device as illustrated in Figure 1; and

Figure 4 is a view in top plan showing a pair of supports in applied position, the associated boat being diagrammatically illustrated.

In the embodiment of the invention as illustrated in the accompanying drawing, 1 denotes a plate adapted to be rigidly held upon the top edge surface of the gunwale of a boat B by the screws 2 or otherwise as may be preferred. The plate is of such dimensions as to have one marginal portion thereof closely approach the outer margin of the top face of the gunwale. This marginal portion is provided with the upstanding spaced knuckles 3 between which is received a knuckle 4 carried by the outer end portion of an elongated, straight member 5. The knuckles 3 and 4 have disposed therethrough a conventional pintle 6 whereby the arm 5 is hingedly connected with the plate 1 so that said plate may be swung outwardly with respect to the boat, as illustrated in Figure 1, or inwardly as illustrated in Figure 2.

2

The outer end portion of the member or arm 5 is provided with an upstanding and relatively short arm 6 and as is clearly illustrated in Figures 1 and 2, the arm or member 5 is of such a length that when the arm 5 is swung inwardly as in Figure 2, the arm 6 will be inwardly but closely adjacent to the side wall of the boat B.

The upper end of the arm 6 is continued by the upwardly and outwardly inclined arm 7 which is continued by the upwardly disposed arm 8, the portions between the arms 7 and 8 as at 9 being disposed on a downward curve on a radius depending upon the extent of spacing between the arms 7 and 8. The arms 7 and 8, together with the portion 9, provide an upwardly facing oar supporting member substantially U-shaped in form when the member 5 is extended outwardly as in Figure 4. When extended as in Figure 1 it is believed to be readily apparent that an oar can be readily maintained or supported in an inoperative position as clearly illustrated in Figure 4.

The inner end portion of the member or arm 5 is provided with the laterally and downwardly disposed arm 10 substantially at right angles to the member or arm 5. This arm or member 10 is so positioned with respect to the knuckle 4 of the member 5 to assure the plate 10 having close contact with the outer surface of the gunwale of the boat B when the member 5 is swung outwardly to bring the device into effective position as clearly illustrated in Figure 1 of the drawings. This arm 10 provides a stop for the arm or member 5 to limit its outward swinging movement when said arm or member 5 is substantially at right angles to the adjacent portion of the boat.

Interposed between the arm or member 5 and the arm or member 10 at opposite sides of the arm or member 5 are the bracing or reinforcing webs 11. As herein embodied, each of the webs 11 is integral with the arm or member 5 and is bent downwardly to a desired angle and then welded as at 12 or otherwise permanently secured to the arm or member 10.

From the foregoing description it is thought to be obvious that an oar rest constructed in accordance with my invention is particularly well adapted for use by reason of the convenience and facility with which it may be assembled and operated.

50 I claim:

1. An oar support for use on a gunwale of a boat in association with an oar lock, comprising a plate adapted to be secured to the top edge of the gunwale and including an upstanding hinge knuckle, an arm having hinge knuckles along one

edge adapted to interengage with the plate knuckle, a pintle pin extending through and pivotally connecting said knuckles, said arm being adapted to be positioned to extend horizontally outwardly from the gunwale, a supporting brace carried by the arm at the said one edge thereof to position against the outer side of the gunwale for maintaining the arm in said horizontal position, and a receiver carried by the arm in a position to receive the blade of an oar when the oar is disposed lengthwise of the gunwale, said brace comprising a plate member secured to the underside of the arm in perpendicular relation therewith for engagement against the outer side of the boat gunwale, and bracing webs between each side edge of the plate member and the corresponding edges of the arm, said arm being of an overall length greater than the width of the gunwale whereby to dispose the U-shaped receiver entirely within the boat when the arm is swung into a position in which it overlies said first mentioned plate.

2. An oar support for use on a gunwale of a boat in association with an oar lock, comprising a plate adapted to be secured to the top edge of the gunwale and including an upstanding hinge knuckle, an arm having hinge knuckles along one edge adapted to interengage with the plate knuckle, a pintle pin extending through and pivotally con-

necting said knuckles, said arm being adapted to be positioned to extend horizontally outwardly from the gunwale, a supporting brace carried by the arm at the said one edge thereto to position against the outer side of the gunwale for maintaining the arm in said horizontal position, and a receiver carried by the arm in a position to receive the blade of an oar when the oar is disposed lengthwise of the gunwale, the said receiver being of U-form and comprising two upwardly diverging sides, the outer end of said arm having a short vertical arm integral therewith, the said vertical arm being joined at its top end with the top end of one side of the U-shaped receiver.
